COMBINATION SIGNALING DEVICE

Hans Samwald, Toronto, Ontario, Canada

Application April 30, 1956, Serial No. 581,766

2 Claims. (Cl. 116—124)

This invention relates to a signaling device adapted for use by persons in distress for signaling their location to a searcher and more especially for use in signaling the location of the distress party to the occupant or occupants of a searching aircraft.

While the present invention is primarily adapted for use by flyers who are forced down at sea possibly at a considerable distance from the nearest land or aircraft carrier, to provide a means whereby searching aircraft can more quickly and accurately locate the person in distress, the invention is also adapted for use by small boats in distress or by those who have been required to abandon a sinking vessel.

It is a further aim of the invention to provide a signaling apparatus which is also adapted for land use to assist searching planes or even searching parties on the ground in locating persons who are lost or otherwise in distress.

Various other objects and advantages of the invention will hereinafter become more fully apparent from the following description of the drawings, illustrating a presently preferred embodiment thereof, and wherein:

Figure 1 is an enlarged elevational view, partly broken away, showing the complete signaling unit;

Figure 2 is an elevational view on a smaller scale illustrating a preferred use of the unit;

Figure 3 is an enlarged fragmentary longitudinal sectional view of a portion of the unit;

Figure 4 is an enlarged fragmentary longitudinal sectional view of another portion of the unit;

Figure 5 is a fragmentary plan view looking toward an inner end of the valve casing as seen in Figure 4, and

Figure 6 is a fragmentary longitudinal sectional view on an enlarged scale of a portion of the bobbin as seen in Figure 1.

Referring more specifically to the drawings, the signaling apparatus in its entirety and comprising the invention is designated generally 8 and includes a combination bobbin and case, designated generally 9, a storage tank 10 for containing smoke, a gas supplying container 11 and an inflatable sack or balloon 12.

The combination bobbin and case 9 includes a bobbin base 13 having a stem or spindle 14 projecting perpendicularly from a central portion of an inner side thereof and having a conventional snap hook 15 anchored to and projecting from its outer side. A tethering line 16 is wound on the bobbin spindle 14 and has one end thereof extending through a bore 17 of the base 13 and which is knotted on the outer side of said base, as seen at 18 in Figures 1 and 6, for anchoring said end of the line to the bobbin 9. The bobbin and case 9 includes an elongated tapered case 19 which fits over the line 16 which is wound on the spindle 14 and which has an enlarged internally threaded end 20 which is threadedly connected to a threaded peripheral portion 21 of the base 13. The other end 22 of the case 19 has a restricted central opening 23 through which the other end of the

2

line 16 extends outwardly from the combination bobbin and case 9. A snap hook 24 is attached to said last mentioned end of the line 16, externally of the case 19.

The smoke storage tank 10 comprises an elongated preferably cylindrical tank which is adapted to contain smoke under pressure and which is provided with a bulged lower end wall 25, in the normal usable position of the tank 10, as illustrated in Figure 2. A valve casing 26 is mounted in an externally flanged opening 27 of the end wall 25, as best illustrated in Figure 4, so that none of the compressed smoke from the tank 10 can escape through the opening 27 around the valve casing 26 to the atmosphere. A valve spindle 28 extends longitudinally through the casing 26 and is slidably disposed in the inner and outer end walls 29 and 30, respectively, of said casing 26. The walls 29 and 30 have aligned central openings 31 and 32, respectively, through which the stem 28 slidably extends. The stem 28 is guided in the opening 31 and extends loosely through the opening 32. A disk type valve 33 is fixed to the stem 28 and is normally held against the inner side of the wall 30 for closing the opening 32, by an expansion spring 34. The spring 34 fits loosely around the stem 28 and has one end bearing against the inner wall 29 and the other end bearing against the valve element 33. A collar 35 is fixed to the stem 28, between the wall 29 and valve element 33 and moves into engagement with the wall 29 to limit the extent of inward movement of the stem 28 toward an open position of the valve element 33. The inner casing wall 29 is provided with a series of apertures 36 around the opening 31 thereof through which the compressed smoke can escape from the tank 10 into the valve casing 26. The outer end wall 30 is detachably mounted to the casing 26 by a threaded connection 37.

A pair of spaced apertured ears 38 project outwardly from the central portion of the end wall 25 to loosely receive therebetween an intermediate portion of a lever 39 which is pivotally connected to the ears 38 by a pivot pin 40 which extends loosely through the intermediate portion thereof and which is supported by the ears 38. An end 41 of the lever 39 is spaced outwardly from the outer valve casing end 30 and has a socket 42 facing toward said valve casing and which engages the outer end of the valve stem 28, as seen in Figure 4. The lever 39 has an eye 43 at its opposite end which is engaged by the snap hook 24, by which said lever is connected to the line 16. A spring 44 is mounted against the outer side of the tank wall 25 between the ears 38 and has ends 45 and 46 which yieldably bear against the lever 39 on opposite sides of the pivot 40 to resist rocking movement of the lever 39 in either direction from its position of Figures 1 and 4. An eye 47 is fixed to and extends from the other tank end 48 and has a snap hook 49 connected thereto.

The gas supplying unit 11 comprises an elongated housing 50 containing a cartridge 51. The housing 50 has a restricted end forming a nipple 52. A bore 53 extends longitudinally through said nipple 52 and has its inner end opening into the chamber 54 of the housing 50 through an inwardly tapered piercing prong 55 of the nipple 52 which also extends into an end of the chamber 54. The other end of the bore 53 opens outwardly of the housing 50. The chamber 54 is sized to slidably receive the cartridge 51 which is provided with a restricted frangible forward end 56 which extends into the forward end of said chamber 54 in which the piercing prong 55 is located. The housing 50 includes a cap 57 which is threadedly and detachably mounted at the opposite end of said housing and against a recessed inner side 58 of which the opposite end of the cartridge 51 seats. An

eye 59 is fixed to and extends outwardly from the cap 57 and is engaged by the snap hook 49 for attaching the housing 50 to the tank 10.

The inflatable sack or balloon 12 has a restricted filling neck 60 which is sized to engage over the nipple 52 and which is secured tightly therearound by a clamp 61.

Assuming that the combination signaling device 8 is to be used by a pilot or occupant of an aircraft which is forced down at sea, the user would attach the snap fastening 5 to one of the numerous eyelets 62 of the life jacket 63 and which is located near shoulder height. The snap fastening 49 is attached to the eye 59 for connecting the smoke tank 10 to the gas supply unit 11, to which the deflated sack or balloon 12 is attached, and the snap fastening 24 is attached to the lever eye 43. The cap 57 is tightened to force the cartridge 51 toward the piercing point 55 so that said point will pierce the frangible end 56 of the cartridge. When this occurs, the interior of the balloon or sack 12 is connected by the bore 53 to the interior of the cartridge 51 so that the gas contained in the cartridge 51, preferably helium gas, will fill and inflate the balloon 12. The balloon is then allowed to rise to the limit provided by the cord 16, preferably to an elevation between four and six hundred feet. The balloon 12 is of sufficient size to support the weight of the units 10 and 11 and to additionally exert a sufficient lifting force on the life jacket 63 so that in the event that the life jacket is defective, the wearer thereof will still be held with his or her head above the water. The spring 34 and the spring end 45 are of sufficient strength so that the valve element 33 will be retained in its closed position while the elevated balloon 12 is held tethered by the line 16.

The balloon 12 may be made of any desired color which will enable it to be most easily seen. The user at intervals by exerting a jerking pull on the line 16 can rock the lever 39 clockwise about its pivot 40 as seen in Figure 4 to displace the valve stem 28 inwardly to thus move the valve element 33 to an open position relative to the opening 32, so that a puff of smoke 64 will escape to the atmosphere through said opening 32. The smoke 64 may also be of any desired color most likely to be seen and to attract attention. The smoke puffs 64 will be in the form of long strips which will be carried by the wind. Thus, a smoke strip may be seen by a searching aircraft at a considerable distance from the balloon 12 and the direction of its longitudinal axis and the direction in which the wind is blowing will indicate to the occupants of the aircraft the direction of the person in distress from the aircraft, to thus greatly simplify locating a person in distress.

The smoke puffs or strips 64 can be released periodically and intermittently, and the tank 10 can be of sufficient capacity so that it may be used in the aforescribed manner for a considerable period of time. The user may also carry extra smoke tanks 10 in waterproof containers of 55 the life jacket 63 to replace an exhausted tank.

It will be readily apparent that the signaling device 8 may be similarly used by persons adrift in a lifeboat, by a disabled small craft seeking assistance, or on land by persons who are lost or disabled.

Various modifications and changes are contemplated and may obviously be resorted to, without departing from the spirit or scope of the invention as hereinafter defined by the appended claims.

I claim as my invention:

1. A combination signaling device comprising an inflatable sack, means containing an inflating medium under pressure which is lighter than air connected to said sack and communicating with the interior thereof and manually operable for discharging the compressed medium therefrom into the sack for inflating the sack, a tank containing compressed smoke attached to and depending from said means, a tethering line, means forming a connection between the tank and an end of the tethering line operable in response of a jerking pull one the tethering line in a direction away from the tank for releasing the compressed smoke in puffs from the tank, an outlet formed in said tank, said last mentioned means comprising a valve closing said outlet, a lever pivotally supported by said tank intermediate of the ends of the lever having one end engaging said valve and an opposite end connected to the tethering line, a valve spring associated with the valve and urging the valve to a closed position and of sufficient strength to withstand the normal pull of the balloon to maintain the valve closed, whereby a jerk on the tethering line will rock the lever to cause the first mentioned end thereof to momentarily displace the valve to an open position against the pressure of the valve spring.

2. In combination with a captive signaling balloon comprising a sack inflated with a gas lighter than air and a tethering line, a tank containing compressed smoke suspended from said balloon, said tank having an outlet, a valve for closing said outlet, a valve spring normally maintaining said valve in a closed position, means supported by said tank engaging a part of said valve and to which the tethering line is attached, said means being operated by a jerking pull on the tethering line for momentarily opening the valve to release a puff of smoke from the tank, and spring means associated with and acting against said aforementioned means in combination with said valve spring to resist movement of said aforementioned means in a direction for opening the valve and for counteracting the pull on the tethering line exerted by the balloon.
